(57) **CLAIM**

The ornamental design for a computer screen with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a computer screen with graphical user interface, showing my new design.

The broken line constituting the outer contour illustrates the computer screen and form no part of the claimed design. The dot-dot broken lines illustrate an ornamental appearance of a portion of the graphical user interface and is a part of the claimed design.
